UNITED STATES PATENT OFFICE.

MARCEL MAZEAU, OF JACKSONVILLE, FLORIDA.

ADJUSTABLE STEEL GRADE BEAM.

Application filed August 19, 1925. Serial No. 51,232.

The present invention relates to grade boards or beams adapted for use in laying sewer and drain pipes, and the like, and has for an object to provide a device for use in maintaining the proper grade of the pipe being laid, and which may be constructed entirely of steel and capable of adjustment to different depths and widths of trenches for different jobs and classes of work.

Another object of the invention is to provide a grade board or beam which when adjusted cannot move or settle out of position even when subjected to heavy load or strains imposed upon the grade beam by workmen or by objects brought into contact with or to bear upon the grade beam.

A further object of the invention is to provide a grade beam of this character the parts of which are normally inseparable so that they cannot be removed and lost and which when set into position cannot be easily knocked out of adjustment so as to maintain the proper grade without continuous readjustment.

The invention still further aims to provide a grade beam of this character with uprights or posts capable of insertion at their lower ends in the earth or which may be attached to the siding when the same is used, the posts having feet or bearing members adapted to rest on the surface of the ground to prevent the settling of the posts and the canting of the same under normal conditions.

A further object is to provide a cross beam which is capable of adjustment not only vertically upon supporting posts but which may be lengthened or shortened to accommodate the grade beam to trenches or excavations of different widths.

Another and further object is to provide a novel mounting for the grade line on the cross beam for adjustably fixing the point of line to correctly position it with respect to the line of pipe under construction.

The above and various objects and advantages of this invention will in part be described in, and in part understood from the following detailed description, the same being illustrated in the accompanying drawings, wherein:

Fig. 1 is a perspective view of a grade beam constructed according to the present invention and as applied to a trench.

Fig. 2 is a detail inner side elevation of one of the posts of the grade beam secured to a siding.

Fig. 3 is a side elevation of the cross beam of the device as applied to the posts, parts being broken away.

Fig. 4 is a top plan view of the cross beam applied to the posts, the latter being in section.

Fig. 5 is a horizontal section taken substantially centrally through the cross beam applied to the posts.

Fig. 6 is a detail perspective view of the intermediate and one of the end side members separated one from the other but in their approximate relative positions.

Fig. 7 is an enlarged transverse section taken through the central portion of the cross beam on the line 7—7 of Fig. 3, and

Fig. 8 is a similar section taken on the line 8—8 of Fig. 3, showing a portion of the adjacent post.

Referring to the drawings 10 designates a pair of posts each of which comprises a T-beam the broad flange of which is adapted to face outwardly while the web 11 is arranged to extend inwardly. The lower end of the post 10 is tapered to a point to provide a prong 12 adapted to penetrate the ground, and the posts are limited in their downward movement by foot pieces 13 which are secured crosswise on the posts a suitable distance above the prongs 12. The foot pieces 13 are of angle iron and are secured to the posts with one flange extending vertically and the other flange lying horizontally. The vertical flanges are adapted to enter the surface of the earth while the horizontal flanges are adapted to lie flat upon the surface of the earth to thereby anchor and support the posts against twisting, canting and downward displacement.

Mounted upon the posts 10 is a cross beam comprising intermediate and opposite end members for relative adjustment and for adjustment to different heights upon the posts. This cross beam comprises an intermediate member 14 of T-beam construction, the broad flange of which is arranged horizontally and uppermost and the web 15 of which extends downwardly and is provided with a longitudinal slot 16 extending throughout a considerable portion of the length of the web 15.

The intermediate member is provided with a slide 17 comprising a metal plate extending across the top of the broad flange of the member 14 and having its ends rolled downwardly about the edges of the broad flange to hold the slide 17 to the plate but

admit the free movement thereof from end to end on the intermediate member. A stop pin 18 is mounted upon the opposite ends of the intermediate member 14 to prevent the slide from being moved accidentally from the intermediate member. The slide carries a thumb screw 19 which is adapted to be turned down through the slide into engagement with the member 14 to hold the slide when adjusted. The slide is provided with a pin or post 20 about which may be looped a grade line 21 extending horizontally above and along the trench.

The member 14 carries opposite end members each of which comprises a pair of flat bars 22 slidably engaging against the opposite sides of the web 15 and beneath the flange 14. Each pair of bars 22 is connected at their inner ends by a bolt 23 which extends through the bars with its intermediate portions extending through the slot 16 so that the bolt 23 may be moved in the slot to slide the bars 22 in and out for extending and shortening the cross beam. The outer ends of each pair of bars is arranged to lie against the opposite sides of the web 11 of the adjacent post 10 and are adapted to be pressed against the web 11 by a pair of clamping irons 24 which are pivotally connected to the pair of bars 22 by a bolt 25 which is spaced inwardly from the outer ends of the bars. The clamping irons 24 extend outwardly from the pivot bolt 25 and bear at their inner edges against the outer faces of the bars 22 opposite the web 11 of the post. The outer ends of the clamping irons 24 are arched about and spaced from the opposite edges of the broad flange of the post 10 and are connected together by a clamping bolt 26.

The clamping bolt 26 is provided with a winged nut 27 adapted to be turned for contracting the clamping irons 24 against the free ends of the bars 22 and impinging the same upon the web 11 of the post to hold the cross beam at the desired height thereon. The bolts 23 at the inner ends of the bars 22 are provided also with winged nuts 28 adapted to bind the bars 22 against the opposite sides of the web 15 of the intermediate member when the desired adjustment is attained. All of the winged nuts are permanently held upon their respective bolts by cotter pins 29 or the like to prevent detachment and accidental loss of the movable parts of the device. The clamping irons 24 are substantially of triangular or bell crank construction so that when their outer ends are contracted they transmit considerable pressure against the sides of the bars 22 and insure a firm grip upon the post.

In order to determine, and to maintain the clamping irons 24 in proper position against the sides of the bars 22, the latter are provided with outturned lugs or flanges

30 at their upper edges and at their free ends beyond the pivot bolts 25 for the purpose of overlapping the clamping irons 24 and holding them from swinging upwardly upon their pivots 25. This maintains the 70 clamping irons in proper alignment with the bars 22.

In use, as shown in Fig. 1, the posts 10 are inserted at their lower ends in the ground with the foot pieces 13 engaging the upper surface of the ground to anchor and hold the posts at opposite sides of a trench 31. The cross beam is raised or lowered upon the posts 10 to the desired height after the clamping irons have been sufficiently released by unscrewing the winged nuts 27. The winged nuts are then again tightened to securely hold the cross beam as adjusted. The winged nuts 28 are released sufficiently to permit the end members of the cross beam 85 to be drawn out or slid inwardly to meet the conditions of the width of the trench or excavation 31. After these adjustments are made, the slide 17 may now be moved over the intermediate member 14 to the desired line of the pipe 32 in the trench. The slide 17 is then secured in adjusted position by the thumb screw 19.

By providing the foot pieces 13 on the posts 10, a rigid structure is obtained which cannot be easily knocked out of adjustment or position and which is capable of sustaining pressure from workmen or the like without changing the adjustment.

When posts 10 are secured to sheathing 100 or sliding 33, or the like as shown in Fig. 2, bolts 34 or nails may be employed and secured through suitable openings formed in the prong portion of the posts.

It is of course understood that various 105 changes and modifications may be made in the details of construction and design of the above specifically described embodiment of this invention without departing from the spirit thereof, and restricted only by the 110 scope of the following claims.

What is claimed is:

1. A grade beam comprising a pair of posts, a cross beam arranged between the posts, said cross beam comprising an intermediate member and a pair of end members adjustably connected with said intermediate member, and clamping means carried by said end members, said clamping means being adapted to embrace said posts for holding the cross beam in a predetermined position.

2. A grade beam comprising a pair of posts, an intermediate member between the posts, end pieces adjustably secured to said intermediate member, clamping means on said end pieces and adapted to bind on said posts, and a guide slidably mounted on said intermediate member.

3. A grade beam comprising a pair of

5 posts, a cross beam including intermediate and end portions, means for adjustably securing the intermediate and end portions together, and means for securing the end portions in vertically adjusted positions upon the posts.

4. A grade beam comprising a pair of posts adapted for vertical position, an extensible cross beam mounted between the 10 posts, clamping means secured to said cross beam at opposite ends thereof and adapted to hold the cross beam in a predetermined horizontal position with respect to the posts, and a guide slidably carried by said cross 15 beam.

5. A grade beam comprising an extensible cross beam, clamps mounted at opposite ends of the beam, a pair of posts adapted for vertical placement, said clamps being adapted 20 to embrace the posts, and a guide slidably mounted on said cross beam.

6. A grade beam comprising the combination 25 of an extensible cross beam, said cross beam being adapted to normally be in substantially horizontal position, a pair of posts, said posts being adapted to be normally in substantially vertical position, means for securing the opposite ends of the cross beam to the posts in a predetermined position, and a guide slidably carried by said 30 cross beam and adapted for horizontal movement therealong, said guide being adapted to be fixed in a predetermined position along said cross beam.

7. A grade beam comprising a pair of 35 posts, an intermediate member arranged between the posts, pairs of bars arranged at opposite sides and opposite ends of the intermediate member, clamping means connecting the inner ends of the bars to the intermediate member, and clamps carried upon the outer ends of the bars to bind the latter against the opposite sides of the posts. 40

8. A grade beam comprising a pair of 45 posts, an intermediate member between the posts, a pair of bars at each end of the intermediate member arranged at opposite sides thereof, a clamping bolt extending through the inner end of each pair of bars for binding the same together and against the opposite sides of the intermediate member and hold the bars in adjusted position, a pair of clamping irons carried upon the outer end portions of each pair of bars, and clamping means connecting the outer ends of the 50 clamping irons to bind the same against said bars and the opposite sides of an adjacent post.

9. A grade beam comprising a pair of 55 spaced posts, an intermediate member between the posts, end members adjustably mounted on the intermediate member, clamps carried upon the outer ends of the end members for securing the same upon the posts when adjusted, and a line carrying 60 slide mounted on the intermediate member for adjustment thereon.

MARCEL MAZEAU.
